(57) **CLAIM**

The ornamental design for an air tire inflating gun, as shown and described.

DESCRIPTION

FIG. 1 is a first perspective view of an air tire inflating gun showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the air tire inflating gun that form no part of the claimed design.

The broken line showing of structural features is included for the purpose of illustrating non-claimed subject matter and forms no part of the claimed design.
